Des. 184,417
Patented Feb. 17, 1959

184,417

COMBINED ADJUSTABLE CIRCUIT BREAKER AND WARNING LIGHT

Joseph L. Bonanno, South Orange, N. J., assignor to The Lionel Corporation, New York, N. Y., a corporation of New York

Application May 9, 1958, Serial No. 50,827

Term of patent 14 years

(Cl. D26—13)

Fig. 1 is a perspective view of a combined adjustable circuit breaker and warning light in accordance with my design;

Fig. 2 is a top view thereof.

Fig. 3 is a side elevational view thereof.

I claim:

The ornamental design for a combined adjustable circuit breaker and warning light, as shown.
